LINT REMOVER

David A. Martin, 2375 Colgate Drive, Costa Mesa, Calif.

Filed Nov. 14, 1963, Ser. No. 77,426

Term of patent 14 years

(Cl. D9—2)

FIG. - 1

FIG. - 2

FIG. - 3

FIG. 1 is a perspective view of a lint remover, showing my new design;

FIG. 2 is an elevational view thereof, taken from the left side of FIG. 1;

FIG. 3 is a bottom view thereof.

The dominant features of my design reside in the portions shown in full lines.

I claim:

The ornamental design for a lint remover, as shown and described.
